GASTON POOTMANS, EUGENE POOTMANS, AND GEORGE POOTMANS, OF REGINA,
SASKATCHEWAN, CANADA.

SHOE-SHINING AND HAT-DUSTING MACHINE.

1,219,148.

Specification of Letters Patent. Patented Mar. 13, 1917.

Application filed April 19, 1916. Serial No. 92,242.

To all whom it may concern:

Be it known that we, GASTON POOTMANS, EUGENE POOTMANS, and GEORGE POOTMANS, of the city of Regina, in the Province of Saskatchewan, Dominion of Canada, have invented certain new and useful Improvements in Shoe-Shining and Hat-Dusting Machines, of which the following is a specification.

10 This invention relates to improvements in shoe shining and hat dusting machines, and the objects of the invention are to facilitate in mechanically polishing shoes and cleaning hats, to render the machine compact in construction thereby occupying a minimum of space and capable of being readily shipped, to permit of the shoe polish being readily applied to the brushes, to cheapen the cost of manufacture and generally to adapt the machine to better perform the functions required of it. With the above and other objects in view the invention consists essentially of the improved construction particularly described and set 25 forth in the following specification and accompanying drawings forming part of the same.

In the drawings,

Figure 1 is a perspective view of the improved machine.

Fig. 2 is a front elevation of the same.

Fig. 3 is a transverse section through the gear casing.

Fig. 4 is a transverse section on the line 35 2-2 of Fig. 2.

Fig. 5 is a vertical section of the polish container showing the ball for applying the polish.

Fig. 6 is a front elevation, partly sectional, of an alternative form of the machine.

Fig. 7 is a sectional elevation of the gear casing showing the means of operating the reciprocating brushes.

45 Fig. 8 is a perspective view of a shoe last on which shoes, when not being worn, are adapted to be secured to facilitate in polishing the same.

Like characters of reference refer to like parts in the several figures.

Referring to the drawings, A represents the shoe shining and hat dusting machine comprising the frame 10 having a gear casing 11 at one end thereof and provided 55 with an angularly disposed foot rest 12 on

the back, the front of the frame being provided with a transversely extending bar 13 operatively supported by the bracket 15 and engaging intermediate of its length with the standard 17 so permitting of shoes being readily positioned for polishing but preventing the clothes of the operator coming in contact with the brush and suffering in consequence.

Rotatably mounted in the frame 10 is a 65 longitudinally extending shaft 18 provided intermediate of its length with a fly wheel 19 and a sprocket 20, one end of the shaft projecting through the casing 11 and carrying a beveled pinion 21 rigidly mounted thereon adapted to mesh with the beveled pinion 22 rigidly mounted on the vertically disposed shaft 23 rotatably supported intermediate of its length by the bracket 24 secured to the upper face of the gear casing 11.

The vertical shaft 23 is provided on the upper end with a hemispherical frame 25 having a concentrically arranged circular brush 26 adjacent to the top thereof and a concave brush 27 located in the lower end, the said brushes being adapted to engage the rim, the lateral walls and crown of a hat in a manner to be made clear hereafter.

The lower end of the shaft 23 rotatably engages with the bearing 28 mounted on the base of the frame 10 and is provided with a horizontally disposed circular brush 29 which coacts with a brush 30 formed substantially like an inverted frustum of a circular pyramid located below the said horizontal brush. The shaft 18 carries a circular brush 31 having two vertically disposed disk shaped brushes 32 arranged along the lateral faces thereof and adapted to coact therewith, the three said brushes facilitating in applying the polish on the shoe being cleaned, while alongside of the said brushes a polishing brush 33 is rigidly mounted on the shaft 18 and consists of rings of 95 felt, velvet or other suitable material provided with flanges 34 also made of the same material, so giving to the brush a substantial U-shape in cross section.

The polish is applied to the brushes 31 and 32 by a unique means consisting of a casing 35 having a plunger 36 slidably mounted therein and capable of being vertically actuated by the screw spindle 37 making threaded engagement with the casing and 110

provided on the upper end with a hand wheel 38 adapted to permit of the spindle being manually operated, the lower face of the plunger being designed to engage with 5 the polishing material and press the same through an orifice 39 in the lower concave of the casing.

This casing carries a cage 40 in which a ball 41 is loosely mounted, and is pivotally 10 mounted on the frame 42 rotatably supported by the eye bolts 43 mounted in the recessed portion 14 of the gear casing 11 thereby permitting of the said polish casing being rotated into an oblique position 15 when not in use, while when applying polish to the brushes 31 and 32 the casing will occupy the position illustrated in Figs. 1, 4 and 6.

The shaft 18 is rotated by a chain drive 20 operatively connecting the sprocket 45 with the sprocket 20, the first said sprocket being rigidly attached to the crank shaft 46 rotatably mounted in the gear casing 11 and operatively connected by a link 47 to a pivotally 25 mounted lever 48 designed to be manually oscillated, the link being operatively connected intermediate of its ends to one end of the spiral spring 49, the other end of which is anchored to the gear casing.

30 Located below the blacking and polishing brushes 31, 32 and 33 is an angularly disposed foot rest 50 provided with a notch 51 intermediate of its length adapted to embrace the standard 17, the said foot rest 35 being adjustably supported intermediate of its breadth by rollers 52 rotatably mounted thereon and being provided on its back edge with a bracket 53 rotatably supporting a roller 54 designed to engage with the vertical 40 wall of the back foot rest 12 in a manner to be made clear hereafter.

This adjustable foot rest is adapted to be fed forwardly during the rotation of the brushes 31, 32 and 33 and may be oscillated 45 about the supporting rollers 52 so permitting the point of the shoe or the instep being polished to the desired extent, the foot rest being retracted to a normal position under the action of the spring 55, one end 50 of which is secured to the back end of the foot rest while the other end is connected to the base of the frame 10.

In Figs. 6 and 7 an alternative form of the machine is illustrated in which the polishing brushes are located intermediate of the blacking and finishing brushes and consist of a circular brush 56 rigidly mounted on the shaft 18 and adapted to coöperate with a pair of reciprocating brushes 57 slidably 55 mounted adjacent to the lateral faces thereof, while below the said brushes a grid foot rest 58 is located consisting of a plurality of vertically disposed plates on which the sole of the shoe is adapted to rest.

60 The brushes 56 are slightly angularly dis-

posed and provided on the back with a plate 59 provided with flanged edges 60 slidably engaging with the guides 61 rigidly mounted on the frame 10, the rear end of each of the plates 59 being provided with a bracket 62 making pivotal engagement with one end of the link 63, the other end of which is rotatably engaged with the crank of the shaft 46. The other elements of the operating mechanism are the facsimile of those already described, the crank shaft 46 being driven by the chain drive 44 engaging with the sprocket 45 mounted on the crank shaft 46 and the sprocket 20 rigidly mounted on the shaft 18.

80 The blacking brushes are similar to those described in connection with Figs. 1 to 5, the only difference being that the foot rest 50 is slightly modified and in this case consists of a grid 64 pivotally mounted intermediate of its length to the spindle 65 and provided on the ends with feet 66 designed to normally hold the grid in an angularly disposed position relatively to the bottom of the frame 10, but permitting of the grid 90 being oscillated to any desired extent as facilitating in polishing the toe or instep of the shoe.

95 In describing the elements of the machine, it has been understood that the shoe is being worn, but should this be not the case and the shoe is loose then it may be placed on the last 67 shown in Fig. 8 which may be then manually positioned and the machine actuated by applying oscillating motion to the lever 48.

100 The assembly of the machine will be readily understood from the foregoing description.

When the machine is in use it is only 105 necessary for the operator to apply oscillating motion to the lever 48 so rotating the several brushes whereupon the shoes are alternately engaged with the brushes 29 and 30 to remove the dirt. The shoe is next 110 placed on the rest 50 and the polish receptacle rotated into a vertical position as shown in Fig. 1, so that the polish extruded through the orifice 39 coming in contact with the rotating ball 41 uniformly applies 115 polish to the face of the brushes 31 and 32 which in turn applies the same to the shoe.

120 When the desired amount of polish has been applied to the front of the shoe that foot is then withdrawn and the shoe rested on the fixed foot rest 12 so that the desired amount of polish may be applied to the heel and back of the shoe and when this has been accomplished the shoe is then placed in contact with the polishing brush 33 and a high 125 polish is given to the shoe thereby.

130 When it is desired to clean a hat the lever 48 is oscillated and the crown of the hat embraced by the circular brush 26 and the concave brush 27 and when the vertical shaft

23 is rotated to the desired speed the brushes coming in contact with the outer periphery of the hat will remove the dust therefrom and give to the same a high polish or finish.

5 In the modification shown in Figs. 6 and 7, the user alternately places his shoes in contact with the brushes 29 and 30, first on the one side and then on the other so that the dirt is removed, whereupon the shoe is 10 next engaged with the brushes 31 and 32 so that the desired amount of polish is applied and the shoe is then withdrawn and placed in contact with the polishing brush 33 resulting in a velvet finish being given 15 to the shoe.

As many changes could be made in the above construction and many apparently widely different embodiments of my invention, within the scope of the claims, constructed without departing from the spirit or scope thereof, it is intended that all matter contained in the accompanying specification and drawings shall be interpreted as 20 illustrative and not in a limiting sense.

25 What we claim as our invention is:

1. A machine of the class described, comprising a frame, a plurality of flat brushes having opposing faces spaced apart, a cylindrical brush arranged between the opposing 30 faces of the flat brushes, means for rotating the brushes, a pivotally mounted polish container, a ball carried by said container and normally engaging the faces of all of said brushes, said ball being freely rotatable in 35 all directions, and means for feeding polish from said container to the ball.

2. A machine of the class described, comprising a frame, a plurality of flat brushes having opposing faces spaced apart, a cylindrical brush arranged between the opposing 40 faces of the flat brushes, means for rotating the brushes, a polish container, a cage mounted on the lower end of said container, a ball loosely mounted in the cage above the cylindrical brush and between the flat brushes, 45 and means for moving the ball into and out of engagement with the adjacent brushes.

3. A machine of the class described comprising a frame, brushes rotatably mounted therein, an oscillating foot rest located below the brushes, rollers rotatably mounted in the foot rest intermediate of the length thereof, a bracket on the back of the foot rest, a roller rotatably mounted in the bracket, and resilient means for retaining 50 the foot rest in a normal position.

4. A machine of the class described comprising a frame, brushes rotatably mounted therein, an oscillating foot rest located below the brushes, rollers rotatably mounted 60 on the foot rest intermediate of the length thereof, and a spiral spring operatively connected at one end to the foot rest and at the other end to the frame.

In witness whereof we have hereunto set 65 our hands.
